Inventor
Thomas B. DeForest.

UNITED STATES PATENT OFFICE.

THOMAS B. DE FOREST, OF BIRMINGHAM, CONNECTICUT.

IMPROVEMENT IN ATTACHING HOOKS AND EYES TO CARDS.

Specification forming part of Letters Patent No. 39,893, dated September 15, 1863; antedated July 3, 1862.

To all whom it may concern:

Be it known that I, T. B. DE FOREST, of Birmingham, of county of Derby, in the State of Connecticut, have invented a new Method of Putting Hooks and Eyes in Cards or Papers; and I do hereby declare that the following is a full and exact description thereof, reference being had to the accompanying drawings, making part of this application.

My invention relates to a method of putting up the hooks and eyes for the market on cards or papers without any sewing or fastening contrivance; and my invention has for its objects a method of putting up the hooks and eyes which shall involve less labor and time, which shall be in every way more economical than any method now followed, which shall involve a more durable and permanent attachment of the hooks and eyes to the card or paper, while at the same time the former may be more readily detached from the latter for use.

In order that those skilled in the art to which my invention relates may fully understand my said invention, I will fully describe it, referring by letters to the accompanying drawings, forming part of this specification, and in which—

Figure 1 is a plan view of one of my cards or papers of hooks and eyes. Fig. 2 is a cross-section at the line xx of Fig. 1. Fig. 3 is a plan view of another modification of my invention. Fig. 4 is a cross-section at the line yy of Fig. 3. Fig. 5 is a partial perspective view of another modification of my invention, and Fig. 6 is a cross-section at the line zz of Fig. 5. In these several figures the parts which are common to the several modifications are indicated by the same letter of reference. Figs. 7 and 8 (marked "Diagram") are illustrations which do not embrace my invention, and which will be particularly alluded to separately hereinafter.

A is the card or paper to which the hooks and eyes are attached. a are the hooks, and b the eyes, which may be of any of the sizes and patterns in use or known.

My invention consists in attaching the hooks along the edge or edges of a card, paper, or equivalent without any looping or sewing, substantially as hereinafter described; and my invention further consists in hanging the

eyes in the hooks when the hooks are fastened on the edge of a card, or its equivalent, substantially as hereinafter described.

In Figs. 1 and 2 the card or paper A is of sufficient width to accommodate the arrangement of hooks a , (shown,) and has formed during its entire length four ribs, (marked 3 4, 3 4.) If only one edge of the card was used, only one set, 3 4, of said ribs would be used. These ribs I propose to form on the strips of card or paper by means of dies or rolls, or in any manner found most convenient.

The strip of card or paper, or papier-maché, or other material, may be of any desired length and proportion and have attached to it any given number of hooks and eyes.

In the ribs 3 4 there are formed, at convenient distances apart, sets of depressions 1 2, 1 2, &c., down even with the main surface of card A , and of a width equal to the width of the shank 5 of the hooks a .

The drawings, at Figs. 1 and 2, show clearly the relative positions of the hooks, eyes, and card A . The eyes b are first placed in the beak of the hook a , in position in which they appear, and the operator then, holding hook and eye in the right hand and the card or paper A in the left hand, slides the beak of the hook over the edge of card A , (see a 7, Fig. 2,) and then presses the shank a down into the recesses 1 2, the Fig. 8 portion, or back of shank, locking over and behind the rib 4, as clearly seen in the drawings. It will be observed that the eye is first slipped into the hook's beak and the hook then placed on the card A , as just described. This operation of putting on the hook can, it will be observed, be performed very rapidly, since there is no looping or weaving, as it were, of the hook through holes, as occurs in all other methods heretofore employed, not embracing a thread or securing device. When the hooks and eyes are to be used, they are easily pulled off of the card, taking the card in one hand and grasping the eye and hook with the other hand.

In the modification shown at Figs. 3 and 4 the hooks and eyes are put together first and then placed on the edge of the card A , in about the same manner as just described of Figs. 1 and 2, but in Figs. 3, 4 the card A is cast, pressed, or otherwise formed of paper or

other suitable material, with cavities or recesses *c*, of the shape shown, instead of having ribs and recesses, as shown in Figs. 1, 2. The cavities *c* are so shaped as to leave the stock in a proper form to sustain the hooks' shanks laterally, and allow their back portion to lock over the points *8*, which latter are made so slight as to easily break out when the hooks are pulled from the card for use.

The drawings show this modification of my invention so clearly that further explanation is needless.

In the modification illustrated at Figs. 5 and 6 the card *A* has only a single rib, *4*, formed in it, instead of two, as seen in Figs. 1 and 2, while the card *A* is shown as if thin on the edge with an auxiliary strip, *i*, placed along to make up sufficient thickness to properly fill the beak of the hook. This piece *i* may be fastened to *A*, or slid in as each hook is laid on edge of *A*.

It has been customary previous to my invention to attach the hooks and eyes to a paper without sewing, but in all cases it has been necessary to introduce the hook or eye, or both, through perforations in the paper—an operation requiring much time and practice, and the hooks and eyes when thus secured to the card cannot be very readily released, as they must be either extricated through the perforation or the paper torn out.

In Figs. 7, 8, diagram, *A* is the paper, and *a b* are the hooks, and *c d* the eyes. This diagram shows two of the best methods known previous to my invention. For one method—that for the hooks and eyes *a* and *c*—the paper *A* is perforated at 1 and 2, as shown, with a longitudinal crimp or crease raised in the paper along the line *x x*. The hook *a* (its beak) is passed down through the perforation 1 and then through perforation 2, the crimp along the line *x x* coming in contact with the tip of the beak at 3. The eye *c* is then passed into position seen, where it is retained in the beak of the hook by the crimp of the paper at *a'*. For the other method shown in this diagram—and the one most used now, I believe—the paper *A* is perforated and crimped in the same manner as for the first method, with the addition of a slit or slot at *e*, through which the eye *d* is passed, as shown. This latter method has been found an improvement on the first and patented as such, it having been found in practice that the first method was imperfect

because of the liability of the eyes *c* to become detached from the hooks *a*.

It will be observed that in my method of putting up the hooks and eyes, although the eye is suspended or hung in the beak of the hook only, the latter is so arranged on the card or paper that the eye cannot escape until the hook shall have been completely detached or disengaged from the card; and it will also be seen that while this is the case, and the hook only has to be attached to the card, the attachment or connection is performed without any passing of the hook or any part of it through perforations, which is a great desideratum, since the manipulation can be so much more rapidly gone through with when the hook has not to be passed through holes or interwoven.

I may remark that it is proposed (to save time and labor in carding or putting up hooks and eyes) to employ machinery for linking the hooks and eyes together and presenting them to the hand of the operative in this condition, ready to be grasped between the thumb and forefinger and stuck onto the card *A*, according to my patent or invention.

According to any of the other methods of putting the hooks on the paper used previous to mine it would be impractical to employ machinery for any portion of the manipulation.

It is probable that with my improved method hooks and eyes can be carded or put up for nearly one-half less than the present cost of this part of the manufacturer's business.

Having explained the nature and objects of my invention and its practical working, and wishing to be understood as not limiting myself in carrying out my invention to any particular mode or to any form or proportion of card or material, so long as the method involved is adhered to, what I claim as my invention, and desire to secure by Letters Patent, is—

The method of attaching the hooks to the card or paper, substantially as hereinbefore described—that is, by passing the beak and shank astride the card and pressing the eyes of the hook into recesses or over ledges, substantially as set forth.

In testimony whereof I have hereunto set my hand this 4th day of October, 1861.

Witnesses: THOMAS B. DE FOREST.
